HOLSTER

Filed Oct. 17, 1927

By

INVENTOR
Robert P. Mees.
AT TORNEY

UNITED STATES PATENT OFFICE

ROBERT P. MEES, OF ST. LOUIS, MISSOURI

HOLSTER

Application filed October 17, 1927. Serial No. 226,705.

This invention relates to a certain new and useful improvement in holsters.

My invention has for an object the provision, as a new article of manufacture, of a holster of such construction as to hold and retain the pistol from accidental displacement or removal and yet permit quick withdrawal of the pistol when the occasion demands.

10 My invention has for another object the provision, as a new article of manufacture, of a holster adapted for support upon a belt and capable of attachment upon and detachment from the belt without necessitating removal of the belt from about the person.

And with the above and other objects in view, my invention resides in the novel features of form, construction, arrangement, and combination of parts hereinafter described and afterwards pointed out in the claims.

In the accompanying drawing,—

Figure 1 is a side elevational view of a holster embodying my invention, the holster being in supported position upon a belt;

Figure 2 is a rear elevational view of the holster; and

Figure 3 is a view similar to Figure 1, looking at the holster from its opposite side and the belt-clip covering-flap of the holster being thrown back.

Referring now more in detail and by reference characters to the drawing, which illustrates a preferred embodiment of my invention, the holster includes a body A conforming in shape, as shown, to the usual revolver or pistol B and formed preferably of a section of leather or other suitable material doubled upon itself, as at 1, to provide outer and inner or front and back walls 2 and 3, respectively, which, in turn, are stitched or otherwise fixed together, as at 4, along their edge, the securing-stitching being preferably re-enforced by end-rivets 5. At the upper or butt-end of the holster, the back-wall 3 is preferably integrally extended, as at 6, for purposes shortly appearing.

As so constructed, the holster A conveniently accommodates the pistol B, whose handle projects outwardly of the holster for

ready gripping in effecting withdrawal of the pistol.

For supporting the holster A upon a belt C, the holster is provided with a clip D. This clip is preferably constructed of a suitable section of sheet metal and in end view is of inverted U-shape, including a back-plate or wall 7 disposed and fixed, as by rivets 8, flatwise upon the rear or back holster-wall 3 adjacent the butt-end of the holster. Suitably spaced from, and integrally connected by a preferably arcuate top wall 9 to, the back-plate 7, is a front plate or wall 10 having a re-entrant or rearwardly presented hook 11 at its lower end, the walls or plates 7 and 10 and the hook 11 and top wall 9 being suitably spaced to more or less snugly correspond with the dimensions of and accommodate the particular belt C, as best seen in Figure 2. In the engagement and disengagement of the holster A with belt C, the front plate 10 is yieldingly sprung to accommodate the belt between the bill of the hook 11 and back-plate 7.

As so supported on the belt C, the metal-clip D is adjacent the clothing of the wearer, and to prevent injury to such clothing and also cover and conceal the clip, the holster back-wall 3 is provided with a flap 12 which is adapted for folding down over both the belt C and clip D and between the belt C and the clothing, as also best seen in Figure 2, the flap 12 at its free end and the holster back-wall 3 being co-operatively provided with snap-couplet members 13—14 for detachably retaining the flap in belt engaging and clip-covering position. By such means, the holster A may be efficiently supported at the proper position upon a belt, upon and from which the holster may be attached and detached without necessitating removal of the belt from the person.

As so supported, there is more or less danger or liability that the pistol B may accidentally drop out of the holster. The holster is accordingly equipped with a strap E, which at one end is fixed, as by a rivet 15 to the front holster-wall 2 adjacent its upper or butt-end, which is adapted for projection over the pistol trigger-guard 16, and

which at its upper end is provided with a snap-eye 17 adapted for detachable engagement with a co-operating snap-button 18 suitably disposed upon the outer face of the extension 6 of the holster-back-wall 3. When so engaged, the free end of the strap E is disposed flatwise on said wall extension, and when so attached, functions to removably retain the pistol B from accidental or otherwise unintentional removal or displacement, but yet, on a jerk upon the pistol, the snap-members 17 and 18 are automatically, as I may say, disengaged, with the result that the strap E does not retard or in any way interfere with a quick withdrawal of the pistol when the occasion should require.

My new holster may be economically manufactured, is simple and durable in structure, and is, as experience has shown, exceedingly efficient in the performance of its intended functions.

I am aware that changes in the form, construction, arrangement, and combination of the several parts of my new holster may be made and substituted for those herein shown and described without departing from the nature and principle of my invention.

Having thus described my invention, what I claim and desire to secure by Letters Patent is:

1. As a new article of manufacture, a holster including an inverted U-shaped belt-engaging clip fixed upon the rear face of the inner wall and adjacent the butt-end of the holster and comprising spaced front and back plates, a top wall connecting said front and back plates, and a hook projecting from the lower end of the front plate and disposed between said front and back-plates, and a flap 40 projecting from said back wall and foldable over said clip, the flap being adapted for detachable engagement at its free end with the holster.

2. As a new article of manufacture, a holster including front and rear walls, the front wall being of reduced length relatively to the rear wall and thereby exposing a portion of the front face of the rear wall, a snap-couplet member fixed upon said exposed portion of the front face of the rear wall, a strap fixed at one end upon the outer face of said front wall and adapted for projection upwardly and rearwardly over the trigger-guard of the encased pistol, and a co-operable snap-couplet member on the free end of said strap adapted for detachable engagement with said first couplet-member for preventing accidental displacement of the pistol.

In testimony whereof I have signed my name to this specification.

ROBERT P. MEES.
